UNITED STATES PATENT OFFICE.

CHARLES F. SPARKS, OF ST. LOUIS, MISSOURI.

BAG-TURNING APPARATUS.

Application filed November 16, 1925. Serial No. 69,438.

This invention relates to mechanical apparatus used in connection with the manufacture of bags, and with regard to certain more specific features, to a method of, and apparatus for turning bags.

Among the several objects of the invention may be noted the provision of a bag turning machine which turns bags and automatically delivers said bags therefrom; the provision 10 of a bag turning machine which has a cyclic operation of such a type that the bag feeding operation to the machine need not be definitely synchronized for perfect and continuous operation; the provision of a machine of the 15 class described which is readily and simply adjustable; the provision of a machine of the class described which will eliminate delays due to the jamming and sticking which are inherent in definitely synchronized bag turning machines; and the provision of a machine 20 of the class described which is automatic in operation, simple and inexpensive in construction, but which has a high output capacity. Other objects will be in part obvious and 25 in part pointed out hereinafter.

The invention accordingly consists of the elements and combinations of elements, features of construction, and arrangements of parts which will be exemplified in the structure hereinafter described and the scope of 30 the application of which will be indicated in the following claims.

In the accompanying drawings, in which is shown one of various possible embodiments 35 of the invention,

Fig. 1 is a vertical section of the machine taken from front to rear and is taken on line 1—1 of Fig. 2;

Fig. 2 is a front elevation of the machine; 40 Fig. 3 is a fragmentary detail section taken approximately on line 3—3 of Fig. 2; and

Fig. 4 is a fragmentary section taken on line 4—4 of Fig. 1.

Corresponding reference characters indicate corresponding parts throughout the several views of the drawings.

In the prior art relating to the turning of bags, the bags have been turned by holding them open end to a wind trunk. The trunk 50 has been provided with suction apparatus whereby an inrushing current of air has been generated. This inrushing current of air drew the bag into the trunk, thereby turning it inside-out or outside-in, depending upon 55 the particular operation or function desired. Thereafter the inrushing current air was cut

off, the bag holding means made releasable and a withdrawing mechanism set into operation, all at once, and usually by some synchronized means. This system required a 60 rather fine degree of synchronization which is not practically operable with bags of varying size, texture and condition of material. Furthermore, such apparatus was difficult to design for making adjustments relative to bag 65 sizes, that is, without complicating the machine beyond practical limits.

Simple, all-manually operable devices have been constructed, but for the larger sizes of bags they tax the strength of an operator to 70 such an extent that output is seriously decreased. The present device obviates the above difficulties.

Referring now more particularly to Fig. 1 of the drawings herewith, there is illustrated at numeral 1 a preferably vertical wind trunk of a substantially rectangular cross section (see also Fig. 2). At its lower end this trunk 1 is provided with an adjustable telescoping portion (of similar rectangular cross section) 75 for purposes of longitudinal adjustment as regards the length of the trunk. A bolt-and-slot combination 5 serves to hold a predetermined adjustment between the telescoping parts 1 and 3. The trunk 1 is braced to vertical A-shaped frames 7 and 9 by means of a brace bar or forging 11.

The A-shaped frames 7 and 9 are upwardly provided with bearings 13 and 15 respectively. These bearings rotatably carry in and 80 between them a hollow cross-shaft 17 to which is permanently fastened a hollow drum or cylinder 18. The cylinder 18 has closed ends 19 and 21 which engage the shaft 17 at points within the bearing areas of said shaft. The 85 shaft 17 and drum 18 may be cast or otherwise formed as a revolving unit. The ends 19 and 21 of the drum function as thrust collars as well as to close in the drum 18. Within the drum 18 the interior of the hollow shaft is 90 made to communicate with the hollow interior of said drum by way of a plurality of openings 23. At the end located at bearing 13, the hollow shaft 17 is plugged shut. At the other bearing 15 the shaft 17 continues out past the 95 bearing as an overhanging shaft. At the end of the overhanging portion it engages an air pipe 25 by means of a stuffing gland 27. The gland 27 permits of relative rotation between the shaft 17 and pipe 25 and yet affords an air-tight joint therebetween. The hollow interior 100 of the pipe 17 communicates with the pipe 25

105

110

by way of said gland 27. The air pipe 25 leads to a main air pipe 29 which is provided with a centrifugal air exhauster or suction blower (not shown). As indicated, the shaft 17 and 5 the air lines 25 and 29 are of ample proportions, so that a copious supply of air may be drawn therethrough. The pipe 29 preferably passes in a direction parallel to the direction of the axis of shaft 17 for reasons to be set 10 out.

The shaft 17 is driven rotatively by means of a pulley 28 fastened thereto, and a belt 30 on the pulley. The belt 30 is in turn driven from a line shaft or the like (not shown).

15 As indicated in the drawings, the surface of the drum 18 has formed therein spaced circumferential grooves 31 (Figs. 1 and 4). These grooves are preferably of a rectangular cross section, and they substantially cover 20 the drum from end to end.

Fig. 1 shows that the front wall 33 of the wind trunk substantially follows the periphery of the drum 18 for a distance of approximately ninety degrees of arc, and at the same 25 time gradually approaches the surface of the drum. At about the uppermost point on the drum, where only a narrow aperture 35 remains between said drum 18 and wall 33, the wall 33 ends. The aperture 35 is of 30 a size adapted to permit smooth passage of a flattened bag therethrough, but to prevent excessive leakage of air, for reasons to be made clear hereinafter.

Formed flatly against the respective sides 35 19 and 21, of the drum 18, are ears or sides 37 and 39 of the curved portion 41 of the wind trunk. These sides 37 and 39 prevent appreciable leakage of air into the wind trunk at the ends of the cylinder 18. The sides 40 of the drum are preferably machined to fit flatly against these ears or sides. A lateral member 43 joining, the sides 37 and 39 and fastened to the inner or rear wall of the wind trunk, serves to hold a quantity of 45 packing material 38 against the surface of drum 18 and in the grooves thereof, thereby preventing leakage of air into the wind trunk at its point of tangency with the drum. It may be noted in Fig. 1, that the inner wall 50 45 of the trunk is formed tangentially with regard to the drum and that inward radially bent tines at the end of the rear wall extend into the circumferential grooves 31, thereby holding said packing 38 in operative 55 position.

Each groove 31 of the drum 18 is made to communicate with the interior of the drum by way of a plurality of holes or openings 47 (see Fig. 4). Hence air may pass from 60 the interior of the curved portion 41 of the wind trunk into the drum 18 by way of such openings 47 as happen to be at said curved portion. In any position of the drum, a plurality of these openings are in the said 65 position at the curved portion 41.

In order to prevent excessive passage of air through the openings 47 which are not at the curved portion 41, each groove 31 is provided with a slideable fitting, concentrically formed finger 49, reaching from the 70 said aperture 35 peripherally to engage the packing material 38 under or behind the wind trunk. From here each finger 49 passes downwardly out of its groove. All the fingers are preferably milled from or 75 formed with a single plate 51 which is bolted to a lateral cross member 53. The member 53 is fastened to the said A-frames 7 and 9. It is to be understood that the fingers may be sprung into their slots where large radii 80 are used, or they may be formed sectionally where necessary.

The cross member 53 also carries at the right-hand end thereof a rearwardly formed and slotted member 55. Adjustably clamped 85 to said slotted member is a take-off rod or bar 57 which serves purposes to be described. The bar 57 is preferably made adjustable in its slot, from a point on the drum center line to some point well to the right thereof. A vertical adjustment might also be employed, if desired.

In order to draw air vertically through the trunk 1, there is provided at each side 90 of said trunk an opening 59. The openings 59 are formed opposite one another at about the point of tangency of the rear wall 45 of the trunk 1 with the drum 18. The positions of openings 59 may be varied in elevation, if desired. Two branch air pipes 61 100 lead from these openings 59 to a portion 63 of the main air line 29. Fig. 1 shows that the portion 63 and the remainder of the line 29 are of equal bores and are aligned. They are held in spaced relationship, end to end, by means of an aligning frame 65. At the spaced portion of said pipes 63 and 29 is placed an automatic shutter valve of the following description.

At the end of pipe 63 is fastened a spider 110 67 in which are cut open radial equally spaced sectors 69. The number of these may be varied, but for example, two are here shown. Each subtends slightly less than ninety degrees of arc. The spider 67 is preferably machined on its outer face. Rotatably and centrally mounted flatly against said spider is a machined disc 71. This disc 71 reaches radially through the open spaced portion between the pipes 63 and 29 and fills 115 this portion enough to prevent a deleterious amount of air leakage. If desired, packing may be provided on the pipes to press against the disc 71. Within the pipes, the disc 71 is provided with approximately ninety degree, oppositely formed sector openings 73 125 (Fig. 3). These openings 73, if the disc 71 is rotated, will of course align with the openings 69 in the spider 67 every ninety degrees of movement. This arrangement then pro- 130

- vides an air valve which, when open, permits withdrawal of air from and up the wind trunk, through the pipes 61 and 63 to the main line 29, to the blower or suction device.
- 5 When this valve is closed, substantially no air rises in the trunk. It should be noted that, even though a relatively loose fit is had between the spider 67 and disc 71, that only a negligible amount of air leaks through
- 10 the valve when it is closed. Ball bearings may be provided for the disc 71, thus eliminating much wear under continuous action.
- In order to rotate the air valve, the disc 71 is flanged at right angles to form a pulley
- 15 surface 75. A belt 76 leading from said surface 75 and over a tight pulley 77 on the said hollow shaft 17, serves to rotate the disc 71 and thereby to operate the valve when the shaft 17 rotates.
- 20 Now, it is desired to have the valve operate only intermittently and to accomplish this, a mechanism is provided whereby the belt driven disc 71 may be locked against rotation until opening of the valve is required. This involves slipping of the driving belt 76 which thereby acts as a slipping friction clutch, ready at all times to operate the valve.
- To hold the air valve in a closed position
- 30 against the tendency of the belt to rotate its disc 71, the pulley surface 75 is flanged outwardly at one edge thereof. The flange 79 thus formed is spirally notched at points 81.
- Pivotedly mounted on said casting 65 is a
- 35 pawl arm 83 provided with a pawl 85 adapted to engage either of the notches 81 to stop rotation of the disc 71. As shown in Figs. 1 and 3, the arm 83 is mounted over the valve so that gravity tends normally to engage the
- 40 pawl with a notch. This engagement is arranged to take place (in the case of either notch) when the openings in the spider 67 and disc 71 are disaligned, that is, when the air valve is shut. The design of the relative
- 45 positionings between openings, notches and the pawl, accomplishes this purpose.
- It is desired to have the air valve operate automatically to open when an operator's hand is in the act of bringing the mouth of a
- 50 bag up to the bottom of the wind trunk. To accomplish this purpose the outer end of the pawl arm 83 is provided with a downwardly extending pivoted rod 87. This rod passes downwardly through a guide 89 formed with the said brace 11. It passes on downwardly to a point immediately adjacent to one end of the mouth of the wind trunk. The rod 87 is made adjustable in length by means of the coupling piece 88, whereby it may be adjusted
- 55 in length when the trunk 1 is adjusted in length. Hence an end knob 91, at the lower end of the rod, can always be brought into juxtaposition with one edge and side of the trunk mouth.
- 60 The operation of the machine is as follows,
- assuming a counter-clockwise rotation of the drum 18 (Fig. 1) and locked position of the air valve; and also operation of the suction blower on line 29:
- The operator grasps a bag B at each corner of the open mouth thereof and thrusts said mouth in proximity to the open lower end of the wind trunk. In so acting, his right hand in raising up, can readily be made to raise the button 91. This action automatically raises the rod 87 and consequently the pawl 85 is raised from one of the notches 81. Hence, immediately the disc 71 is free to and does rotate under action of the friction belt 76. The air valve is thereby opened, and air is drawn from the trunk 1 into the line 29, by way of the upper sideward ports 59 and pipes 61. The main current of air in the trunk is upward, inasmuch as the aperture 35 at the drum edge does not permit passage of air as well as does the lower open end of the trunk. The air comes through the trunk in a puff and draws the bag upwardly into the trunk, thereby turning the bag as the operator holds it. The previously lower edge of the bag is now positioned approximately opposite the sideward ports 59. Hence the air passing outwardly from said opposite ports 59 tends to flatten or hold flattened the drawn-up and turned bag. The now lower edge of the bag retains its more or less flattened position in the hands of the operator.
- Next, the operator to insure straightening of the bag, gives it a slight tug downwardly, whereat his hand releases the button 91 and consequently the pawl 85 drops down to engage a said notch 81. Under ordinary conditions of operation the above events take only an instant of time and only one opening of the air valve is therefore required. Hence the pawl 85 usually engages the next notch in order to hold the valve shut. At each operation of the pawl with a notch the air valve is in a shut position. If, however, the operator should inadvertently or otherwise hold up the button 91, the air valve would merely continue to open and close until the operator released the button 91. Hence the bag would in any case be substantially held in the dotted line position L shown in Fig. 1.
- The position L of the bag indicates that its bottom edge (now upward) cooperates with the surface of drum 18. The length of the trunk is adjusted for such cooperation. The cooperation takes place at the time the bag is turned in the manner previously described. It is to be remembered that air is continuously flowing from the interior of the drum 18 by way of the shaft 17 to the suction side of the air valve, that is to line 29 by way of pipe 25. Hence air is entering the open portions of the grooves 31 within the curved portion 41 of the wind trunk from whence it enters the drum 18 to be drawn out

at pipe 17. This action of the air sucks or holds the bag edge to the drum surface. If the bag is held in the trunk 1 (in position L) an unnecessary period of time, no harm has 5 been done, inasmuch as the drum merely slips under the bag, that is, when there is resistance on the bag at its lower end.

Now, when the bag is released by the operator from its position L, the up-current of 10 air in the trunk 1 is cut off in the manner described, thereby automatically preventing said current from drawing up the now free lower end of the bag and hence crumpling it in the wind trunk.

15 Therefore the bag at the instant the operator releases it, is suspended by gravity in the trunk with its now upper edge held to the drum surface by suction. It is in a desirable flat position. The drum 18 is of course rotating and immediately upon release of the bag carries it upwardly through the portion 41 of the trunk as well as to and through the aperture 35. As the bag rises, its position on the drum 18 becomes more secure as more 20 suction area of the grooves is automatically applied to the bag. It is evident that the apertured drum 18 comprises a movable wall for the wind trunk adapted to have various portions of its surface cyclically cooperate 25 with the trunk to become a wall therefor. Each portion of the drum at some time is instantaneously a part of the wind trunk, and the cyclic order is a progressive one.

As the bag emerges from the aperture 35 30 (see position M of bag) it passes over the tines or fingers 49 in the grooves 31. The tines are downwardly beveled or tapered to facilitate such passage. The leakage of air into the drum 18 past the fingers 49 is enough 35 to hold the bag to the drum surface as the bag descends at the rear thereof. This leakage may be adjusted by design. Gravity aids in holding the bag to the drum surface as the bag descends, that is until the bag begins 40 to traverse the lower arc of the drum circle. The aid of gravity is then changed to an action tending to pull the bag from the drum surface. However, the suction of inrushing air is enough to hold the bag to the drum 45 surface until the forward edge of the bag reaches the point N (Fig. 1). At point N, the gravity component of pull acting on the bag is about a maximum, and the tendency to accelerate the bag upwardly at this point, 50 results in the portion of the bag at point N leaving the drum surface. In order to make the descent of the bag certain, downwardly extending ribs or fins 56 may be formed with the fingers 49. These defeat any tendency of 55 the bag to stay with the drum surface as it proceeds. As the drum continues to rotate and successive elements of the bag come to the point N, they leave the drum until the bag 60 assumes the position O, wherein the front 65 portion is arched over the lower cross-rod 57.

At this juncture the free weight of unsupported bag material has increased to an amount whereat the remaining portion of the bag behind point N is quickly stripped from the drum surface by said weight, back 70 to the rear edge P of the bag. This action puts the bag into position Q and falling downwardly. It is arched well over the rod 57. Next, it drops downwardly over the rod 75 with approximately one-half the bag on either side of the rod. From this position the bag may readily be removed for stacking.

It is to be understood that the leakage at any point on the travel of the bags may be increased or decreased as desired, merely by 80 changing the widths of the fingers. For instance they might be tapered to give a varying holding force at the bag, whereby it could be released at any predetermined time. The rod 57 may be adjustably positioned to catch 85 the bags most advantageously.

If an operator should fail to remove bags from the rod 57 for a period, no harm is done, 90 inasmuch as they merely gather there, one on the other, until removed.

The fact that the air valve in line 29 operates intermittently does not cause appreciably varying suctions to take place in the line 25 and drum 18, inasmuch as centrifugal 95 blowers have an operating characteristic such that when the inlet volume of air is decreased by cutting down the inlet area, the blower does not increase the velocity of air in the decreased areas appreciably. The slippage in the blower is merely increased without substantially lowering pressures in the open suction pipes. It is obvious that one size of trunk will accommodate several sizes of bags both as to length and spread.

It is to be understood that the drum 18 may 100 be gudgeoned instead of provided with the through-shaft, as described and other like changes might be made without invalidating the principles of construction set forth.

It is instructive to note, as above, that the drum 18 forms a movable part of the wind trunk, broadly speaking. It forms a longitudinally movable wall therefor.

In view of the above, it is believed that the various features of this invention will be 115 clear without further elaboration, and it will be seen that with the apparatus herein described, the several objects of the invention are achieved and other advantageous results attained.

As many changes could be made in carrying out the above construction without departing from the scope of the invention, it is intended that all matter contained in the above description or shown in the accompanying drawings shall be interpreted as 125 illustrative and not in a limiting sense.

I claim:

1. A bag turning machine comprising a flattened wind trunk having edge walls, an 130

- inlet for drawing a bag into said trunk, and sideward outlets in the edge walls thereof for drawing air through the trunk to turn a bag therein, the said positioning of the ports being adapted to draw air for turning the bag substantially from and through the corners of said bag from the interior of the bag, whereby the bag is at once turned and positively flattened.
10. 2. A bag turning machine comprising a wind trunk for turning the bags, a longitudinally movable wall therein, longitudinal grooves in the movable wall, means for drawing air into and across each groove, whereby the bags are held to the wall and fingers in the grooves for decreasing the hold on the bags at a predetermined point.
15. 3. A bag turning machine comprising a wind trunk for turning the bags, a longitudinally movable wall therein, longitudinal grooves in the movable wall, means for drawing air into and across each groove, whereby the bags are held to the wall, fingers in the grooves for decreasing the hold on the bags at a predetermined point, and oppositely formed ports at the sides of said trunk near the movable wall for drawing air through the trunk.
20. 4. A bag turning machine comprising a wind trunk for turning the bags, a longitudinally movable wall therein, comprising a drum, peripheral grooves in the drum, means for drawing air into and across each groove, whereby the bags are held to the wall, and oppositely formed ports at the sides of said trunk near the movable wall for drawing air through the trunk, whereby the bags are turned into the trunk and flatly held therein against said movable wall.
25. 5. A bag turning machine comprising a wind trunk for turning the bags, a longitudinally movable wall therein, comprising a drum, openings arranged around the complete periphery of the drum, means for drawing air into and across each opening, whereby the bags are held to the wall, and oppositely formed ports at the sides of said trunk near the movable wall for drawing air through the trunk, whereby the bags are turned into the trunk and flatly held therein against said movable wall, and means for stopping air flow from said openings as the bags are successively turned and held to the movable wall.
30. 6. A bag turning machine comprising a wind trunk for turning bags, a hollow rotatable drum cooperating with the trunk, peripheral grooves on the surface of the drum, means for drawing air into the drum by way of said grooves, whereby turned bags in the trunk are held to the drum surface to be ejected from the trunk.
35. 7. A bag turning machine comprising a wind trunk for turning bags, a rotatable drum cooperating therewith, spaced ports arranged around the periphery of said drum and means for drawing air into said ports, whereby turned bags are held to the drum surface to be ejected from the trunk.
40. 8. A bag turning machine comprising a wind trunk for turning bags, a longitudinally continuously movable wall therein, spaced openings positioned along the entire periphery of the movable wall, and means for drawing air into and across each opening, whereby the bags are held to the wall and where by a bag may be received at any instant by the wall without specifically timing the feeding of bags.
45. 9. A bag turning machine comprising a wind trunk for turning bags, a rotatable drum cooperating with the trunk having openings arranged completely around its periphery, means for drawing air through the openings, whereby the drum is adapted to be continuously in condition to hold the bags to its surface and eject them from the trunk.
50. 10. A bag turning machine comprising a wind trunk for turning bags, a movable wall therein adapted to have given portions of its surface cyclically cooperate with the trunk, openings spaced completely around the periphery of the wall, and means for drawing air into said openings, whereby bags may be held to said wall at any instant to be ejected from the trunk.
55. 11. A bag turning machine comprising a wind trunk for turning bags, a movable wall therein adapted to have given portions of its surface cyclically cooperate with the trunk, openings spaced completely around the periphery of the wall, means for drawing air into said openings, whereby bags may be held to said wall at any instant to be ejected from the trunk and means for partially obstructing the passage of air through said openings at predetermined points for decreasing the suction hold on the bags.
60. 12. A bag turning machine comprising a wind trunk for turning bags, a movable wall therein adapted to have given portions of its surface cyclically cooperate with the trunk, openings spaced completely around the periphery of the wall, means for drawing air into said openings, whereby bags may be held to said wall at any instant to be ejected from the trunk, means for partially obstructing the passage of air through said openings at predetermined points for decreasing the suction hold on the bags, and means for stripping the bags from the wall completely at a predetermined point.
65. 13. A bag turning machine comprising a wind trunk for turning bags, a movable wall therein adapted to have given portions of its

surface cyclically cooperate with the trunk, openings spaced completely around the periphery of the wall, and means for drawing air into said openings, whereby bags may be held to said wall at any instant to be ejected from the trunk, means for turning the bags into the trunk comprising openings located laterally of the said wall in the trunk whereby

bags may be drawn into the trunk and flattened on the said movable wall by withdrawing air from the sides of the bag. 10

In testimony whereof, I have signed my name to this specification this 14th day of November, 1925.

CHARLES F. SPARKS.
